United States Patent

Des. 236,649
Patented Sept. 2, 1975

236,649

COMBINED FLOOR LAMP AND TABLE

Kenneth K. Knoepfle, 350 NE. 55th Terrace,
Miami, Fla. 33137

Filed Dec. 11, 1973, Ser. No. 423,657

Term of patent 7 years

Int. Cl. D26—05

U.S. Cl. D48—20 D

FIG. 1

FIG. 2

FIG. 6.6

FIG. 7

FIG. 1 is a front elevational view of a combined floor lamp and table showing my new design, the shade being omitted for purposes of disclosure;

FIG. 2 is a rear elevational view thereof;

FIG. 3 is an elevational view as taken from the left of FIG. 1;

FIG. 4 is an elevational view as taken from the right of FIG. 1;

FIG. 5 is a top plan view thereof;

FIG. 6 is a front elevational view of the complete combined table lamp and table of my design;

FIG. 7 is a rear elevational view thereof;

FIG. 8 is an elevational view thereof as taken from the left of FIG. 6;

FIG. 9 is an elevational view as taken from the right of FIG. 6; and

FIG. 10 is a top plan view thereof.

I claim:

The ornamental design for a combined floor lamp and table, as shown and described.
